UNITED STATES PATENT OFFICE.

JAMES MCK. CABLE, OF BROOKLYN, NEW YORK, ASSIGNOR OF ONE-HALF
TO MICHAEL SPALL, OF SAME PLACE.

FENDER.

SPECIFICATION forming part of Letters Patent No. 531,155, dated December 18, 1894.

Application filed April 5, 1894. Serial No. 506,390. (No model.)

To all whom it may concern:

Be it known that I, JAMES MCK. CABLE, of Brooklyn, in the county of Kings and State of New York, have invented a new and useful Improvement in Fenders, of which the following is a specification.

My invention relates to an improvement in fenders for use in connection with cars impelled by horse, cable or electric power along surface roads; the object being to provide a fender which will receive and carry along with it, without serious injury, the body of a person struck by the car until the car can be stopped and to further provide a fender, which may be utilized for either end of the car and capable of being shifted with facility from one end of the car to the other, according to the direction in which the car is to travel.

20 A practical embodiment of my invention is represented in the accompanying drawings, in which—

Figure 1 is a view of a car in side elevation, showing the fender in position for use at one end of the car and the fender support at the opposite end of the car in its withdrawn adjustment. Fig. 2 is a vertical section through the fender, and portion of the platform to which it is attached. Fig. 3 is a front view of the fender and platform. Fig. 4 is a view in detail, showing the catch which holds the fender in removable adjustment to the platform; and Fig. 5 is a view in detail, showing means for advancing and returning the fender support by a crank.

25 The platforms at the opposite ends of the car are provided with fender supports quite similar in all respects and the explanation of one will be therefore sufficient to a clear understanding of both. The car platform is denoted by A. It is provided on its under side with a pair of sockets B, B' for the reception of a pair of longitudinally sliding bars C. The bars C are conveniently provided with removable stops c at their inner ends, for the purpose of limiting their outward movement and have notches c', c'' formed in their upper sides for the reception of a spring actuated bolt or locking pin D, fastened to the front 30 of the car and adapted to hold the supports

either in their outwardly adjusted or inwardly adjusted positions, as required.

The outer ends of the bars C are provided with downwardly curved portions c³, for the reception of trunnions e projecting laterally from brackets e' on the rear sides of the ends of the guard or fender E. The trunnions e are located near the lower edge of the guard, so that there is a tendency on the part of the guard, when struck, to tilt over toward a horizontal position. The guard E is provided along its lower edge and preferably up its sides with a pneumatic cushion e² for preventing the bruising of any object which it might strike and it is held normally in an oblique position at an angle of forty-five degrees, more or less, with the surface of the track by means of a pair of coilsprings F, F' which surround guide rods f, f' attached to the upper rear portion of the guard E. The lower or rear ends of the guide rods f, f' are provided with enlarged heads f² which are received through enlarged portions f³ of openings in brackets G, fixed to the front of the platform A.

75 The guide rods f, f' are locked to the brackets G by sliding catches g, carried by the brackets G, and adapted to slide down into position to partially cover the enlarged portion f³ of the openings which receive the heads f² of the guide rods and thereby prevent the said guide rods from escaping from the brackets so long as the catches g are advanced. The guide rods f, f' are also provided with disks or collars f⁴ a short distance from their heads f² free to slide on the guide rods.

80 The springs F, F' are adjusted between the disks f⁴ and the rear of the guard so that while the springs are sufficient to hold the guard normally in its inclined position, shown in Figs. 1 and 2, they will readily yield and permit the guard to assume a position more nearly horizontal when any considerable weight is received upon the guard. The catch g, when it is advanced, rests between 90 the face of the bracket G and the disk f⁴, as shown in Fig. 4.

95 In operation, it is intended that the lower edge of the guard shall move along in proximity to the rails and when the guard is 100

struck by an object, the weight of that object will tilt the guard over into a position so nearly horizontal as to carry the body along until the car is stopped.

5 When it is desired to run the car the opposite end foremost, the guard may be removed from the end of the car where it has been in use by simply withdrawing the catches *g* and lifting the guide rods *f, f'* out of the brackets 10 *G* and the trunnions *e* of the guard out of the slots *c* and then adjusting the guard to the opposite end of the car in reverse order. The supports *C* at the end where the car has been in use may be then slid back under the 15 platform by lifting the catch bolts *D*.

In case it is found desirable to advance and return the supporting bars *C* simultaneously, it may be done by providing the bars with rack teeth, as shown in connection with the bar 20 *C', Fig. 5*, and locating a shaft *H* transversely underneath the platform and providing it with a pair of spur wheels *h* to engage the rack teeth on the bars *C'*, the shaft *H* itself being provided with a crank *h'* for turning 25 the wheels *h* in the one direction or the other.

and thereby advancing or returning the supporting bars.

What I claim is—

1. The combination with supports mounted to move outwardly and inwardly at a car platform and means for locking the supports in their advanced and withdrawn adjustments, of a removable fender hinged below its center to the supports and having a rearwardly tilting movement toward a horizontal position, substantially as set forth. 30

2. The combination with the tilting fender and a suitable support for it, of a guide-rod extending rearwardly and downwardly from its upper portion and provided with an enlarged head, a bracket secured to the platform and provided with an opening to receive the head of the guide-rod and a catch secured to the bracket for locking the guide-rod to the bracket, substantially as set forth. 40

JAMES MCK. CABLE.
